(57) **CLAIM**

The ornamental design for an excercise device with removable weight, as shown and described.

DESCRIPTION

FIG. 1 is a perspective view of an exemplary embodiment of an exercise device with removable weight showing our new design;

FIG. 2 is a top plan view thereof;

FIG. 3 is a bottom plan view thereof;

FIG. 4 is a front elevational view thereof;

FIG. 5 is a left side elevational view thereof, the right side elevational view being a mirror image of the right side elevational view and thereof not illustrated; and,

FIG. 6 is a perspective view of another exemplary embodiment of an exercise device with removable weight showing our new design. The bottom and right side of this exemplary embodiment are identical to the corresponding views of the previous embodiment, with the exception of the broken line structure.

The broken lines are shown in the views for illustrative purposes only, and form no part of the claimed invention. The rear view of the device is not part of the claimed invention and is therefore not illustrated.
